INTERCHANGEABLE CONNECTION BOX FOR
CARD TABULATORS

Francis Guy Sydenham English, West Croydon,
England, assignor to The Accounting & Tabu-
lating Corporation of Gt. Britain Limited,
London, England

Application January 11, 1933, Serial No. 651,202
In Great Britain February 12, 1932

2 Claims. (Cl. 235—58)

This invention relates to interchangeable connection box for card tabulators having a sensing pin box and a plurality of adding and/or printing elements which are arrested by means of stops set by the pins which have passed through holes in a card. These adding and/or printing elements are grouped in units each unit serving to add and print items of a particular classification. Such a machine is described in Powers' 5 U. S. patent specification No. 1,245,502.

In order to transmit movement from the sensing pins to the stops a connection box is employed comprising extension rods leading from the pins to the stops so that when any pin is 15 raised the corresponding stop is also raised by the agency of the intervening extension rod.

In some classes of work it is required to add the same item on two or more units or groups of adding elements and in order to enable this 20 to be done the connection box has to be removed and replaced by another box in which some of the extension rods are branched so as to actuate the stops of two or more units. Frequently the connection box is built into the machine and its 25 removal and replacement involves considerable time and labour inasmuch as the adding mechanism has to be removed in order to enable the connection box to be taken out.

The object of the present invention is to provide 30 a form of connection box which can be readily removed from the machine and replaced by another without disturbing the parts of the machine.

According to the present invention the connection box is provided with supports adapted to 35 engage with guides on the tabulator frame, whereby the connection box may be slid into position in the machine, means being provided for locking the connection box in the correct position.

40 Preferably, also, the connection box is provided with means for locating it in the correct position, for example, it may carry a pivoted arm on the end of which is mounted a roller or pin running on a track when the box is being pushed into position, this track being formed with a recess 45 into which the roller or pin moves when the connection box has reached the desired position and definitely locates it.

One construction according to the invention is 50 diagrammatically illustrated by way of example in the accompanying drawing, in which—

Fig. 1 is a perspective view of the connection box in position in the guides provided on the tabulator;

55 Fig. 2 is an end view of the connection box;

Fig. 3 shows a detail of that portion of the box which engages with the guides;

Figs. 4 and 5 show to an enlarged scale details of the means for adjusting the final position of the connection box.

In the construction illustrated in the drawing the tabulator frame (not shown) is provided with horizontal guides A at each side. The guides A are formed with a slot A¹ with which engages a foot on the connection box, there being one 65 foot at each side of the box. These feet are in reality compound members made up of two angle bars B and C (see Fig. 3).

The angle bar B is secured to the under-side of the connection box by means of screws D 70 which pass through slots or elongated holes in the angle bar B, whereby the latter can be adjusted longitudinally with regard to the connection box.

The angle bar C is secured to the bar B by 75 means of screws E passing through slots in the vertical portion of the angle bar C, whereby the bar C can be adjusted vertically with regard to the bar B. The horizontal portion C¹ of the bar C is adapted to engage with the slot A¹ in 80 the guide A.

The connection box carries at each end an arm F pivoted to the box at F¹ and carrying at one end a pin F² which, when the connection box is being inserted, engages with the upper surface 85 of the slot A¹ in the guide A.

In order that the operator may push the connection box into place without searching for the exact location, each guide A is provided with a recess A² (see Fig. 2), into which the pin F² moves when the connection box has been pushed in to the desired extent. The pin F² is moved into this position due to the action of a weighted bar K and cooperating linkage hereinafter described.

95 In order to provide an adjustment for the connection box in the direction of its movement along the guides A, the pins F² which engage with the recesses A² in these guides, are eccentrically mounted on discs F⁴ which in turn are rotatably mounted in bushings F⁵ of arms F. Thus by revolving discs F⁴ the position of the connection box with regard to the tabulator pin box can be 100 adjusted within fine limits. Set screws F⁶ are provided to hold the discs F⁴ in the positions to which they have been adjusted.

105 The ends F³ of the arms F remote from the pins F² are connected through links G to arms H respectively pivoted to plates J and J¹ secured one at each end of the connection box. The links 110

G are pivoted to the arms H between the ends of the latter and the free ends of the arms H are connected by a heavy rod K which, when the connection box has been pushed in to the fullest extent, causes, by its weight, the pins F² to engage with the recesses A².

In order to release the connection box the rod K is raised, thereby freeing the pins F² from the recesses A². The rod K also serves as a handle for pushing the connection box in and out.

It will be understood that when inserting a connection box the sensing pins must be down. If the sensing pins are up and the stops are down the distance between them will not be sufficient to permit insertion of the connection box. In order to ensure that the pins and stops are in the correct relative position, a stop card is run into the machine prior to the insertion of a new connection box whereby the pins are held down, the stops also remaining down.

What I claim is:—

1. For use with a tabulating machine having connection box guides, a connection box comprising a body, supports on said body adapted to engage with and move in said guides whereby

said box may be slid into position in the machine, an arm pivoted to the connection box body, a projection on said arm adapted to run in one of said guides, and means tending to turn said arm about its pivot whereby the projection on the arm enters a recess in said guide when the box is pushed in a predetermined extent.

2. For use with a tabulating machine having connection box guides, a connection box comprising a body, supports on said body adapted to engage with and move in guides on the tabulator frame whereby the connection box may be slid into position in the machine, arms pivoted to the connection box body, one at each end thereof, a projection on each arm, each of said projections being adapted to run in one of said guides, a weighted bar, and operative connections between said bar and the projection-carrying arms, whereby said bar serves not only as a handle to manipulate the connection box, but also, by reason of its weight, to cause the projections to engage with recesses in their respective guides when the connection box has been pushed in to the fullest extent.
